UNITED STATES PATENT OFFICE.

WILLIAM C. WHITE, OF SCHENECTADY, NEW YORK, ASSIGNOR TO GENERAL ELECTRIC COMPANY, A CORPORATION OF NEW YORK.

ELECTRIC DISCHARGE DEVICE.

Application filed April 27, 1926. Serial No. 104,960.

My present invention relates to vacuum devices and more particularly to means for producing and maintaining a high vacuum in thermionic devices.

5 In the operation of thermionic devices or electronic devices operated substantially independent of gas ionization, and particularly in such devices which are commonly known as power tubes and which usually comprise a 10 hollow metal anode fused or welded to a glass superstructure, it is sometimes difficult to maintain a high vacuum. This difficulty is due to the fact that gases may be more or less continuously evolved from the different parts 15 of the discharge device, and in some cases, as where glass is sealed to metal, very slow air leaks sometimes develop.

The forces producing gas effects in a tube 20 are roughly proportional to the power involved, and any overload or voltage transient is particularly likely to cause a tube to evolve gas. The gassing effect is cumulative, and although the first gassing may be small and apparently unimportant, the small amount of 25 gas evolved makes the tube even more susceptible to overload with the result that very soon the tube may evolve gas at a relatively high rate. At such times the tube becomes unfit for use and is discarded, destroyed or 30 turned for a complete reexhaustion.

According to the present invention a getter bulb is employed to produce and to maintain the vacuum in a thermionic device at or 35 below a predetermined pressure. In carrying my invention into effect a bulb or tube of approximately the size of an ordinary 25 watt incandescent lamp is mounted on a thermionic device of the power type. The bulb is provided with a material which may be vaporized at will as gas accumulates within the discharge device, and is connected to the power device by means of a passageway which is 40 short, and wide enough to permit the getter material in the bulb to effectively clean up the 45 gases in the discharge device.

The novel features which I believe to be characteristic of my invention are set forth with particularity in the appended claims. My invention itself, however, both as to its 50 organization and method of operation will best be understood from reference to the following specification taken in connection with the accompanying drawing in which Fig. 1 represents a view partly broken away of a getter tube or bulb employed to maintain the vac-

uum in a discharge device; Fig. 2 shows in elevation the metal to be evaporated and the holder therefor, the latter being partly broken away; Fig. 3 is an elevation of an electric discharge device of the power type with a getter bulb mounted thereon; Figs. 4 and 5 show circuit arrangements for automatically controlling the operation of the getter bulb.

Referring to the drawing, I have indicated at 1 the anode member of a power tube 2, in 60 the present instance, a pliotron, although the type of tube employed is immaterial so far as the invention is concerned. A glass sleeve 3 having a reentrant portion 4 is connected to anode 1 by means of the usual metal seal 5. 70 A filamentary electrode, not shown, is mounted within anode 1 and is provided with a pair of leads 6.

Adjacent the upper end of sleeve 3, is a getter bulb of approximately the size of the ordinary 25 watt incandescent lamp. The getter bulb comprises a container 7, connected by a relatively short and wide extension 8 with the interior of the discharge device 2. Mounted within the container 7 is a suitable wire 9 75 provided with a forked end portion 10 which is adapted to be permanently secured to a perforated metal holder 11 which may be made of molybdenum or other suitable material and within which is placed a suitable vaporizable material, for example, an alkaline earth metal, which in the vapor state or in the form of a film will energetically combine with gases. Conveniently a piece of magnesium coated calcium wire 12 is used. The ends of the 80 container or holder 11 are provided with ears 13 which are bent over to thereby retain the getter metal in position in the holder. A filamentary conductor 14, which is made of tungsten, surrounds the holder 11 and is connected 85 to a pair of nickel or molybdenum leads 15. The portions of leads 15 and wire 9 which extend through the glass press 16 may, if lead glass is used, be made of Dumet wire.

The discharge device 2 is evacuated in any 100 manner desired until a predetermined pressure is obtained. After the device has operated for some time, gas may be evolved, either from the parts of the discharge device itself, or a certain amount of gas may be 105 introduced by leakage. If, at such times, a current is supplied to the filament 18 of the getter bulb 2, a small amount of calcium will be vaporized by heat from the filament 14 and the metal vapor and film deposited 110

on the walls of the getter bulb will combine with the gas present in the discharge device to reduce the pressure therein to a desired minimum value which will usually be well 5 below a micron. The getter vapor and successive layers of getter material deposited on the walls of the getter tube are extremely effective in combining with all common gases and the by-products of the reaction are so 10 stable that the reaction may be repeated many times during the life of the discharge device without impairment of the device in any manner.

In the operation of the getter tube it may 15 be advantageous under certain conditions to flash the filament 14 either constantly or at substantially regular intervals of time. Such operation may be desirable owing to the 20 tendency of a calcium surface to become contaminated in absorbing gases and thereby lose its power as a getter. Originally, the calcium wire which is used in connection with the getter tube is provided with a magnesium coating which will effectively protect the calcium 25 from oxidation for a considerable period of time, even when directly exposed to the action of the atmosphere.

If desired, the discharge device may, to 30 a considerable extent, be evacuated originally by means of the getter bulb alone rather than by means of a pump. Furthermore, discharge devices which have been discarded on account of very slow air leaks or because of gassing may be again operated efficiently 35 when provided with a getter bulb of the type described. With a getter bulb permanently attached to a discharge device, it is possible to maintain a pressure in the discharge device which is very much lower than that obtained 40 by the use of a pump, and as a result of the low pressure thus produced, it is possible, without increasing the size of the anode, to operate a discharge device at voltages which are very much higher than would be 45 possible with a less perfect vacuum.

With a getter bulb of the size indicated, the pressure in a relatively large power tube, as for example, a 10 k. w. tube may be maintained at .1 to .0001 microns as long as any 50 active getter material remains in the bulb. Since the amount of getter material flashed off at intervals is very small compared with the amount of getter material originally placed in the holder 11, the arrangement disclosed 55 provides a simple, inexpensive and very effective means of producing and maintaining a high degree of vacuum in a discharge device thereby prolonging the useful life of such a device far beyond the limit reached 60 without the aid of an attached tube 1.

If desired the lead-in wire 9 may extend through the glass press 16 so that a potential may be applied thereto as well as to the filament 14. In this manner the getter tube 65 may act as a two-element rectifier. Further-

more, the use of the getter holder as an electrode may allow measurements of getter metal evaporation to be made if desired.

I have indicated in Figs. 4 and 5 two ways in which the operation of the getter tube 2 70 may be automatically controlled. It is well known that in a 3-element tube the degree of vacuum may be determined by measuring the flow of positive ions to a negatively charged electrode such as the grid. When the grid is 75 negative, for example, the grid current which is a so-called positive ionization current is directly proportional to the gas pressure in the tube, other factors being constant. In actual devices this current may vary from 10 80 to 100 micro-amperes for a good vacuum in a high power tube. In the arrangement disclosed in Fig. 4, I have taken advantage of the relationship between negative grid current and the vacuum in the discharge device 85 to automatically control the operation of a getter tube associated with the discharge device. In this figure, I have designated the thermionic vacuum device by the reference numeral 2 and the getter bulb by the reference numeral 7. The grid current passes through the resistance element 17. In order, however, to use only the negative grid current a rectifier unit, such as a kenotron 18 is employed. Kenotron 18 and a relay 19 are connected in series with each other and in shunt with the resistor 17. When the vacuum in the discharge device 2 decreases, the negative grid current rises and operates relay 19. Relay 19 may, of course, be adjusted to operate at any predetermined value of current. Energization of relay 19 closes a circuit for a coil 20 controlling a switch 21 in circuit with a source of energy 22 and the heater filament 14 of the getter tube. The current supplied to filament 14 vaporizes the calcium in the getter tube and thereby restores the high vacuum in the discharge device 2 whereupon the grid current decreases and relay 19 is deenergized. 100

If desired the filament 14 of the getter tube may be energized at substantially regular intervals by means of a timing device 23, as indicated in Fig. 5. Although I have illustrated in Figs. 4 and 5 means for automatically controlling the heater coil of the getter bulb it will be obvious that in either of these arrangements the circuit of the heater coil may be closed continuously if desired, so that a relatively small amount of calcium may be vaporized continuously during the operation of the thermionic device. 115

Although I have disclosed a relatively small getter bulb, it may be found desirable to vary the size of the bulb employed, and for a larger power tube as, for example, a 100 k. w. tube I may employ not only a larger getter bulb than that indicated but also a larger amount of getter material. 120

What I claim as new and desire to secure 130

by Letters Patent of the United States, is:—

1. In combination, a thermionic vacuum device, a container mounted in said device, said container being provided with a material capable of combining with all common gases, a heating coil within said device and surrounding said container, and means for energizing said coil at will to vaporize a part of said material and thereby maintain a high degree of vacuum in the thermionic device.
2. In combination, a thermionic device comprising an evacuated container, said con-

tainer including a hollow anode and a vitreous portion sealed to the anode, an auxiliary container mounted on said vitreous portion and communicating with the interior of the vacuum of the thermionic device, said auxiliary capable of combining with common gases and means for vaporizing said material, said means comprising a heater coil operable at will.

In witness whereof, I have hereunto set my hand this 26th day of April, 1926.

WILLIAM C. WHITE.

CERTIFICATE OF CORRECTION.

Patent No. 1,712,370.

Granted May 7, 1929, to

WILLIAM C. WHITE.

It is hereby certified that error appears in the printed specification of the above numbered patent requiring correction as follows: Page 3, line 18, claim 2, before the word "capable" insert the words "container being provided with a material"; and that the said Letters Patent should be read with this correction therein that the same may conform to the record of the case in the Patent Office.

Signed and sealed this 11th day of June, A. D. 1929.
